UNITED STATES PATENT OFFICE

108,631

DESIGN FOR A COMBINED ASH RECEIVER AND EXTINGUISHER

Walter L. Webster, Colorado Springs, Colo.

Application July 15, 1937, Serial No. 70,471

Term of patent 14 years

To all whom it may concern:

Be it known that I, Walter L. Webster, a citizen of the United States of America, residing at Colorado Springs, county of El Paso, and State of Colorado, have invented a new, original, and ornamental Design for a Combined Ash Receiver and Extinguisher, of which the following is a specification, reference being had to the accompanying drawing, forming part thereof, wherein:

Figure 1 is a front perspective view of a

combined ash receiver and extinguisher showing my new design.

Figure 2 is a rear perspective view thereof, and Figure 3 is a transverse sectional view, taken on the line 3—3 of Figure 1.

I claim:

The ornamental design for a combined ash receiver and extinguisher, as shown.

WALTER L. WEBSTER.
